TABLE FRAME

Oscar J. Wiethoff, Hollywood, Calif.

Application April 14, 1950, Serial No. 9,210

Term of patent 14 years

(Cl. D33—14)

To all whom it may concern:

Be it known that I, Oscar J. Wiethoff, a citizen of the United States, residing at Hollywood, in the county of Los Angeles and State of California, have invented a new, original, and ornamental Design for Table Frame, of which the following is a specification, reference being had to the accompanying drawing, forming part thereof.

In the drawing:

Fig. 1 is a perspective view of a table frame, showing my new design;

Fig. 2 is a top plan view.

Fig. 3 is a side elevation thereof.

I claim:

The ornamental design for a table frame, as shown.

OSCAR J. WIETHOFF.
